UNITED STATES PATENT OFFICE.

WILLIAM HARKNESS, OF NEW YORK, N. Y.

AUTOMATIC FIRE-EXTINGUISHER.

SPECIFICATION forming part of Letters Patent No. 323,578, dated August 4, 1885.

Application filed July 1, 1884. (No model.)

To all whom it may concern:

Be it known that I, WILLIAM HARKNESS, of the city and State of New York, have invented an Improvement in Automatic Fire-Extin-
5 guishers, of which the following is a specifi-
cation.

Fire-extinguishers have been made with a valve secured at the end of a water-pipe by a frame in which is a cross-bar attached by a
10 fusible solder that melts when the temperature of the air rises to about 150° Fahrenheit and the valve drops. In this character of valve
two difficulties exist. The first arises from the
15 fact that there is a lateral pressure upon the
soldered cross-bar, which tends to prevent a
central and accurate bearing upon the valve,
and the valve is liable to leak, and if it does
there is difficulty in rendering the valve tight;
20 and the second difficulty arises from the fact
that the pressure of the water alone is de-
pended upon to move the valve and throw
the support and cross-bar out of the way.

My invention relates to the combination,
25 with the valve, of a two-part axial support, by
means of which the valve is compelled to take
an even bearing upon its seat, and a spring
that is under compression and acts to move
the axial support entirely away from the
30 valve so soon as the fusible solder that holds
the bars forming the axial support in place
has softened by the heat. By this device the
risk of the valve leaking is lessened, and the
certainty of the valve opening automatically
35 is promoted.

35 In the drawings, Figure 1 is a vertical sec-
tion, and Fig. 2 is an elevation, of my improved
fire-extinguisher. Fig. 3 is a section, at the
line $x-x'$, Fig. 2. Fig. 4 is an elevation, partly
40 in section, of the axial support in a slightly
modified form. Fig. 5 is a sectional plan of
the same at the line $x'-x'$; and Fig. 6 is a sec-
tional plan at the line $y-y'$ of Fig. 4, showing
45 the manner of holding the lower end of the
vertical bar when it is made in one with the
upper axial bar.

The coupling a is to be screwed to the ver-
tical branch b of a supply water-pipe, and the
lower end of this coupling a forms the seat for
the valve d . Around the coupling a is a
50 screw-thread upon which is screwed the ring
 e of the frame f , and this frame f passes into

the notches at the edges of the valve d and
steadies such valve. Upon the frame f there
are lugs or projections f' upon which the
valve rests when it is open. Around the 55
edges of the valve d there are inclined saw-
tooth projections i , and there are upon the
surface of the valve outside its bearing for the
valve-seat the studs k , the object of these
studs and teeth being to convert the margin 60
of the valve into a distributor to separate the
water into small streams as it issues from the
pipe a and to cause it to act upon the fire to
the best advantage. The corrugated deflect-
ing central cone, l , gives an outward direction 65
to the water, and the holes n allow a portion
of the water to pass down to any fire that may
be directly below the fire-extinguisher. The
edges of the ring e project in the form of ser-
rations or corrugations, which aid in scattering 70
the water, and they also facilitate the grasp-
ing of the ring to turn the same and screw the
valve up firmly to its seat.

Below the center of the valve there are the
axial bars p q . The lower end of the bar q 75
rests upon the frame f at the bottom part.
The bars p q rest upon each other endwise,
and the upper end of the bar p rests against
the center of the valve. These parts, being in
line with each other, support the valve firmly 80
and centrally, and very little power is required
to support these parts laterally. In some in-
stances I support these parts laterally by the
cross-bar r , having a hole in the center for the
reception of the ends of p and q , where they 85
come together. The ends of this bar r are
soldered to the frame f , with a solder that
melts at a low temperature—say 150° Fahrenheit—
so that the bar ceases to be a support to
the axial bars at the desired temperature; and 90
in order to throw the axial bars entirely away
from below the valve when the solder melts I
employ the spring s , which is received be-
tween the supports t t upon the frame f , and
this spring is under compression, so that its 95
resistance throws off the bar and breaks the
axial bars the instant the solder at u becomes
sufficiently soft. I remark that the ends of
the bars p q are rounding, so that they will
turn freely as the spring moves them.

In cases where it is desirable to secure the
end or ends of the bar r by the fusible solder

at any other place than that shown in Fig. 2, the same can easily be effected, as it is not necessary to place such bar horizontal. In Figs. 4, 5, and 6 this bar is shown as vertical, 5 in which case it only requires to be soldered at the lower end. The bar r' is preferably made at its upper part as a tubular sleeve, into which is received the axial bar p and the rounded upper end of the axial bar q , and the 10 fusible solder is applied at u between the lower part of the bar r' and the side of the frame f at the bottom thereof. In this construction, as well as in the form shown in Figs. 1, 2, 3, the pressure against the valve is received end- 15 wise upon and in line with the straight axial bars, and when the solder at u melts by the heat the spring s presses the axial bars away and the valve opens.

If the axial bar p , the bar r' , and its tubular 20 sleeve r^2 were all in one piece, the endwise pressure upon p might injure the soldered joint at u . This may be prevented by passing the lower end of the bar r' into a mortise behind the plate u' that is soldered at u to the 25 frame f , as seen in Fig. 6. The position of this plate u' is indicated in Fig. 4 by dotted lines.

It is to be understood that when the ring of the frame is screwed to the coupling-pipe the 30 valve is thereby pressed against its seat, and it is supported against that pressure by the axial bars.

I am aware that a single bar or stem has been used to support the valve in a fire-extinguisher; also, that a support in two pieces 35 has been used, one of which is diagonal to the axis of the valve. In the first-named form the central stem has to move endwise the same distance that the valve is opened; and in case 40 of slight obstruction the valve only partially opens. With supports that are not in line with the valve-axis the valve is liable to leak, because the ram action of the water, produced by opening or closing the faucet, is not taken 45 in a straight line upon its support, and the support is liable to bend or give way. With my improvement the spring throws the parts entirely off when the solder melts; hence the valve opens fully and suddenly; but when the 50 valve is closed no leakage is likely to arise, because the supporting devices are in the axial line of the valve, and there is no lateral action from the water-pressure.

I am also aware that a stationary rim or 55 deflector has been used to divide up the water

after the valve falls within the rim; but the rim is inoperative unless the valve falls the entire distance. By my improvement the distributor, being upon the valve itself, is always operative, regardless of the distance the valve 60 may descend.

I claim as my invention—

1. The combination, with the water-pipe and valve-seat, of a valve, a frame with a ring screwed upon the coupling above the valve-seat, two bars in line with each other and with the axis of the valve abutting against each other and against the valve and frame, respectively, a support secured by solder for the central part of the two bars, and a spring 70 to throw the bars out of line with each other when the solder melts, substantially as set forth.

2. The combination, with the water-supply pipe and valve-seat in an automatic fire-extinguisher, of a valve having a projecting 75 water-distributing rim around it, with perforations and saw-tooth projections with inclined surfaces at their inner sides, and the studs k , and an axial support for the valve that is liberated by the action of the heat, 80 and a frame and ring screwed upon the coupling above the valve-seat, between which and the serrations of the valve the water issues, substantially as specified.

3. The combination, in an automatic fire-extinguisher, of a supply-pipe, a valve at the 85 end of the same, a frame connected with the supply-pipe, two bars, p q , in line with each other and having rounding ends and resting at the top against the valve and the bottom 90 against the frame, and an arm secured to the frame by solder and having a hole through it for the reception of the ends of the bars p q , substantially as set forth.

4. The combination, with the valve and 95 frame in a fire-extinguisher, of two abutting bars in line with each other and resting at the lower end upon the frame and at the upper end against the under side of the valve, a support for the central part of the bars formed 100 as a tube, having a bar projecting therefrom, which bar is secured by fusible solder to the frame, and a spring to remove the bars when the solder melts, substantially as specified.

Signed by me this 26th day of June, A. D. 105 1884.

WILLIAM HARKNESS.
